US0D1019392S

(12) **United States Design Patent** (10) **Patent No.:** **US D1,019,392 S**
(45) **Date of Patent:** **** Mar. 26, 2024**

(54) **BOTTLE**

(71) Applicant: **MARY KAY INC.**, Addison, TX (US)

(72) Inventor: **Zachary Webb**, Addison, TX (US)

(73) Assignee: **MARY KAY INC.**, Addison, TX (US)

(**) Term: **15 Years**

(21) Appl. No.: **29/841,215**

(22) Filed: **Jun. 3, 2022**

Related U.S. Application Data

(62) Division of application No. 29/719,397, filed on Jan. 3, 2020, now Pat. No. Des. 959,280.

(57) **CLAIM**

The ornamental design for a bottle, as shown and described.

DESCRIPTION

FIG. 1 is a top perspective view of a bottle showing my new design;

FIG. 2 is a front view of the bottle shown in FIG. 1;

FIG. 3 is a back view of the bottle shown in FIG. 1;

FIG. 4 is a right side view of the bottle shown in FIG. 1;

FIG. 5 is a left side view of the bottle shown in FIG. 1;

FIG. 6 is a top view of the bottle shown in FIG. 1;

FIG. 7 is a bottom perspective view of the bottle shown in FIG. 1;

FIG. 8 is a top perspective view of a second embodiment of a bottle showing my new design;

FIG. 9 is a front view of the bottle shown in FIG. 8;

FIG. 10 is a back view of the bottle shown in FIG. 8;

FIG. 11 is a right side view of the bottle shown in FIG. 8;

FIG. 12 is a left side view of the bottle shown in FIG. 8;

FIG. 13 is a top view of the bottle shown in FIG. 8; and,

FIG. 14 is a bottom perspective view of the bottle shown in FIG. 8.

The dashed lines in FIGS. 1-14 are included for the purpose of illustrating portions of the bottle that form no part of the claimed design.

1 Claim, 14 Drawing Sheets
